UNITED STATES PATENT OFFICE.

DAVID S. BISSELL, OF PITTSBURG, PENNSYLVANIA, ASSIGNOR TO THE R. D. NUTTALL COMPANY, OF ALLEGHENY, PENNSYLVANIA.

DESIGN FOR A ROLLED BAR.

SPECIFICATION forming part of Design No. 32,294, dated February 27, 1900.

Application filed December 1, 1899. Serial No. 738,922. Term of patent 14 years.

To all whom it may concern:

Be it known that I, DAVID S. BISSELL, a citizen of the United States, residing at Pittsburgh, in the county of Allegheny and State of Pennsylvania, have invented or discovered a certain new and original Design for Rolled Bars, of which the following is a specification.

In the accompanying drawings, forming a part of this specification, Figure 1 is a perspective view of my new design for rolled bars, and Fig. 2 is a transverse section of the same on an enlarged scale.

As shown in the drawings, the leading feature of my design consists of the web or body portion 1, of a considerable thickness, and flanges 2 along the edges of the web, the greatest transverse of said flanges being considerably less than the thickness of the web. The

outer walls of these flanges incline inwardly from or approximately from the planes of junction of the flanges with the web, so that the smallest transverse dimension of the flanges is approximately one-third of the thickness of the web.

Having described my invention, what I claim as new, and desire to secure by Letters Patent, is—

The design for a rolled bar, as herein shown and described.

In testimony whereof I have hereunto set my hand.

DAVID S. BISSELL.
